UNITED STATES PATENT OFFICE.

EDWIN S. PIPER, OF BRISTOL, CONNECTICUT, ASSIGNOR OF ONE-HALF TO
S. EMERSON ROOT, OF SAME PLACE.

ROTARY NOZZLE-HEAD FOR WATER-MOTORS.

SPECIFICATION forming part of Letters Patent No. 380,691, dated April 10, 1888.

Application filed December 22, 1886. Serial No. 223,245. (No model.)

To all whom it may concern:

Be it known that I, EDWIN S. PIPER, residing at Bristol, in the county of Hartford and State of Connecticut, have invented certain new and useful Improvements in Rotary Nozzle-Heads for Water-Motors; and I do declare the following to be a full, clear, and exact description of the same, reference being had to the accompanying drawings, which form a part 5 of this specification.

My invention relates to an improvement in nozzle-heads for water-motors, the object being to produce a head carrying several nozzles, each of different size, adapted to relieve the 15 rotating nozzle-frame from the pressure of the water and to compensate for wear, and combining simplicity and cheapness of construction with durability and general efficiency in use.

With these ends in view my invention consists in a nozzle-head having certain details of construction and combinations of parts, as will be hereinafter described, and pointed out in the claim.

In the accompanying drawings, Figure 1 is 20 a view in perspective of a nozzle-head embodying my invention, together with a portion of a water-wheel. Fig. 2 is a view of the head in front elevation, and Fig. 3 is a view of 25 it in central longitudinal section.

As herein shown, the forward end of the water-supply pipe A is provided with a bearing consisting of a frusto-conical cap, B, having its tapering face or side and flat end ground 30 to form a bearing-surface, and provided in its tapering face and upon its under side with a discharge-port, C, of forward pitch.

The frame D is provided with a circular series of wings, E, inclined outwardly from its 40 rear to its forward end, and respectively having inclined water-passages F, conforming in inclination to the pitch of the discharge-port, with which their inner ends are brought into alignment by the rotation of the frame.

Nozzles G, each of different size, are located 45 in the respective wings and form extensions of their water-passages. A central opening or recess, H, extending forward into the frame from the rear face thereof, adapts it to fit over 50 the bearing or cap upon which it rotates, the

walls of such opening or recess being ground to form a close joint between the two surfaces.

A pivot, I, located in the center of the frame and entering the center of the flat end of the cap, secures the frame to the said cap. All 55 wear between such frame and cap is compensated for by readjusting the said pivot, which consists of a screw left unthreaded where passing through the frame.

The rear edge of the frame is provided with 60 a slot, J, for and located in line with each wing, such slots receiving a spring-actuated pawl, K, pivoted to the cap and holding the frame in its several positions of adjustment upon the bearing.

A yoke, L, secured to the forward end of the frame, carries a spindle, M, having an operating-wheel, N, by which the frame is rotated, secured to its outer end.

The described head is located close to the 70 water-wheel O, which receives the water direct from the nozzles.

In using my improvement the frame is rotated to bring the water-passage of a large or small nozzle into alignment with the discharge-port, according to the power required and to, 75 the pressure or head of the water. In this way the amount of water consumed is made to depend upon the power required with obvious economy.

Under my invention the frame is relieved 80 of the pressure of the water, wear is reduced to the minimum, and leakage avoided. Furthermore, without breaking the water, it gives it advantageous direction upon the wheel.

I would have it understood that I do not 85 limit myself to the exact construction and combination of parts herein shown and described, but hold myself at liberty to make such changes and alterations as fairly fall within the spirit and scope of my invention.

I am aware that a nozzle-head having a 90 frame carrying a series of parallel cylindrical nozzles each of different discharging capacity and adapted to be rotated to bring them into alignment with a single aperture communicating with a water-supply is not new. I am 95 also aware that a head having a series of cylindrical tangential water-passages and a discharge-port for each is not new, and that it 100

is old to centrally pivot a conical cap having discharge-openings. I do not, therefore, broadly claim any of these constructions, but only the particular construction shown and described herein.

Having fully described my invention, what I claim as new, and desire to secure by Letters Patent, is—

In a nozzle-head for water-motors, the combination, with a hollow conical bearing having its larger end open and adapted to be secured to a water-supply pipe, its smaller end closed to form a flat bearing-face, and a discharge-port of forward pitch in its side, of a rotary frame coned out to fit over such conical bearing and the flat face thereof and ad-

justable for wear thereupon, and provided with a circular series of inclined water-passages conforming in size at their inner ends to the said discharge-port and gradually tapering at their outer ends, and each being of different discharging capacity, and a pivot passing through such head and entering the flat face of the conical bearing, substantially as set forth.

In testimony whereof I have signed this specification in the presence of two subscribing witnesses.

EDWIN S. PIPER.
